INJECTOR-EJECTOR BOAT CLEANER

Geoffrey L. McCartney, Atlanta, Ga.

Application December 6, 1950, Serial No. 199,439

2 Claims. (Cl. 114—185)

1

My invention relates to boat cleaners generally but more in particular to an injector-ejector boat cleaner which uses the force of water moving through the same either to bring water into the boat or to remove the water from the boat.

The operation of removing water from boats is well known in the prior art and has necessitated the use of divers bailing mechanisms ranging from hand operated devices to elaborate pumping systems. Considerable effort has also been put forth to provide owners of small boats with hand pumps and light power-operated mechanisms serving not only to draw water for cleaning purposes but also acting as a means of removing the water which has either leaked in or been deliberately placed in the boat for cleaning. The disadvantage of most of these systems lies not only in the expense to the small boat owner, but also in the fact that the device is usually cumbersome and must be handled and lifted from one end of the boat to the other to relieve the various compartments of water or bilge.

It is an object of the present invention to provide an automatic pump, operated by the water in which the boat is moving, to draw accumulated water from off the inside bottom of the boat or to bring in other water for cleaning the boat at the will of the operator.

It is another object of the invention to provide such a pump which is inexpensive to manufacture and which may be secured for use to the gunwale of any small type craft.

It is a further object of the invention to provide an injector-ejector pump for small fishing boats which may be hinged to the gunwale of the boat so that the same may be let into the water for use in either bringing water into the boat or removing water from the boat, and which may be folded or hinged inside the boat when not in use.

Further objects and advantages of the invention will become apparent in the course of the following detailed description when viewed together with the accompanying drawing in which:

Fig. 1 is a front end view of a boat cleaning device made in accordance with the teachings of the present invention, the same being shown as attached to the gunwale of a small boat.

Fig. 2 is a side elevational view of the device shown in Fig. 1.

Fig. 3 is a broken side view of a tube member of the invention, the same being shown closed to water passing therethrough.

Fig. 4 is a broken rear view of the illustration shown in Fig. 1.

2

In the drawing, numeral 10 designates a boat of the shape generally conforming to that of the conventional small fishing boat.

My invention is adapted to be positioned on the gunwale 11 of the boat by means of two U-shaped metal brackets 12 and 13 bent to conform more or less to the inside batten or shear clamp 14 and wedged against the same by means of jack screws 15. The brackets are spaced apart in the manner shown, and each is provided with one long upper leg 16 extended horizontally out over the boat gunwale 11, the legs being bent in the manner shown so as to stand flatwise vertically. Pivottally attached respectively to these legs are metal strips 17 and 18, the lower ends of which are bent around and bolted or otherwise affixed to a length of tubing material constituting a Venturi housing designated generally by the numeral 19.

20. The housing 19 consists of tubing material of any desired size with preferably a truncated cone or funnel-shaped leading end 20. The opposite end of the housing 19 is provided with a transverse slot 21 cut through only a portion of the tube and adapted to slidably receive a valve plate 22. The valve plate 22, in the present instance, is kept from being lost by attaching the same to the tube end by means of a chain 23.

As shown in Fig. 2, I have prepared a second length of tubing 24 which completes the Venturi action as will be described later. This tube 24 is set through the top wall of the housing 19 with the lower end terminating on the longitudinal axis and being beveled as shown. The tube 24 is set at a low angle and has its upper end prepared to receive a length of flexible hose 25 which is of sufficient length to reach any of the compartments along the length of the boat defined by the boat ribs.

For a description of the device as a means of drawing water from a boat, reference is directed to Fig. 2 which shows the boat 10 riding in water 26 and being provided with my invention attached to its gunwale 11 with the cone end 20 of the Venturi housing 19 facing the forward end or bow of the boat. The valve plate 22 is removed from its slot 21 to allow water to pass through the Venturi housing 19.

Let it be assumed that a quantity of water is inside the boat, whether from a leak in the boat bottom, or whether put there deliberately by the boat operator for cleaning purposes. With the device positioned as shown, it is readily apparent that forward movement of the boat will cause water to move through the housing 19 from front to rear, thus creating a draft or

suction through the tube 24, the amount of suction being governed by the speed of the boat through the water. The boat operator, by means of the flexible hose, may suck or drain any or all of the compartments in the boat while the boat is being propelled through the water, without resorting to docking his boat or turning the same upside down on the shore.

Now let it be assumed that the boat operator desires to bring water into the boat for cleaning or rinsing purposes. By placing the valve plate 22 into its slot 21 in the housing 19, water is prevented from going through the housing 19 and is forced, by the movement of the boat, upwardly into the smaller tube 24 and through 15 the flexible hose 25 as shown in Fig. 1. As soon as sufficient water has been forced into the boat, the operator may then remove the valve plate 22, which immediately starts the sucking action to drain the water from the boat in the manner described above.

The device is simple in its construction and easy to manufacture. When not in use the Venturi mechanism may be hinged over the gunwhale to hang inside the boat or may be removed completely by loosening the jack screws 15. The device as shown and described is readily adaptable to various small craft, and the length of the depending strips 17 and 18 may be made to hold the housing 19 below the water line of boats 30 of many sizes.

The device is highly advantageous to fishermen using small boats wherein all equipment, tackle and even the fish are placed on the floor boards of the boat until the boat is finally docked for cleaning. Since the device not only injects water into the boat, but also ejects the same water, the fisherman is permitted to clean the boat perfectly while bringing it to the dock after his trip.

It will be obvious that my invention provides a needed article of great convenience and usefulness, and that while I have illustrated and described my invention in a very practical embodiment without attempting to show other embodiments, various modifications and changes may be made without departing from the scope of my invention as defined in the appended claims.

I claim:

1. Injector-ejector type apparatus for cleaning a boat while the boat is moving through water comprising, an elongated hollow housing, means for suspending said housing from the gunwhale of a boat so that water will enter through

5 the forward end of said housing as the boat moves forward through the water, a small hollow tubular member projecting through a wall of said housing at an acute angle with respect to the longitudinal axis of said housing at a point spaced from the ends of the housing and having the lower end of the member lying substantially along the longitudinal axis of said housing, flexible hose means connected to the upper end of 10 said tubular member, and valve means adjacent and connected to the trailing end of said tubular member, said valve means being selectively operable to block the flow of water from the trailing end of said tubular housing and inject water from within said housing upwardly through said tubular member when closed and to open the trailing end of said housing for the flow of water therefrom when open so as to eject water downwardly through said tubular member.

2. Injector-ejector type of apparatus for cleaning a boat while the boat is moving through water comprising, a hollow tubular housing having a trailing end and an enlarged funnel-shaped forward end, means for suspending said housing from a boat so that water will enter the forward end of said housing as the boat moves forward through the water, a smaller hollow tubular member projecting through a wall of said housing at an acute angle with respect to the longitudinal axis of said housing at a point spaced from the ends of the housing and having the lower end of the member beveled to lie substantially along the longitudinal axis of said housing, flexible hose means connected to the upper end of said tubular member and extended into the bilge portion of the boat, and valve means adjacent and connected to the trailing end of said tubular member, said valve means being selectively operable to block the flow of water from the trailing end of said tubular housing and inject water from within said housing upwardly through said tubular member when closed and to open the trailing end of said housing for the flow of water therefrom when open so as to eject water outwardly through said tubular member.

GEOFFREY L. McCARTNEY.
